RAILWAY TRAFFIC CONTROLLING APPARATUS

Filed March 18, 1930

UNITED STATES PATENT OFFICE

RONALD A. McCANN, OF SWISSVALE, PENNSYLVANIA, ASSIGNOR TO THE UNION SWITCH & SIGNAL COMPANY, OF SWISSVALE PENNSYLVANIA, A CORPORATION OF PENNSYLVANIA.

RAILWAY-TRAFFIC-CONTROLLING APPARATUS

Application filed March 18, 1930. Serial No. 436,753.

My invention relates to railway traffic controlling apparatus, and particularly to apparatus of the type involving a railway switch together with signals governing traffic over the switch, which switch and signals are controlled from a distant point such as a dispatcher's office. One feature of my invention is the provision of novel and improved means for controlling the approach locking of the switch in systems of this character.

I will describe one form of apparatus embodying my invention, and will then point out the novel features thereof in claims.

The accompanying drawing is a diagrammatic view showing one form of apparatus embodying my invention.

Referring to the drawing, the reference characters 1 and 1^a designate the track rails of a stretch of railway track which I will call the "main" track. These rails are divided by insulated joints 2 to form three track sections A—B, B—C and C—D, of which the middle section may be termed the "main" section, and the two outer sections may be termed "approach" sections. Located in the main section B—C is a switch E, which when reversed, diverts traffic from the main track into a side track Z.

Each section of the main track is provided with the usual track circuit comprising a battery 3 and a track relay designated T with a distinguishing exponent. The track circuit for the main section B—C is extended in the usual way to the fouling point of the side track Z.

The switch E is provided with an operating mechanism F which is controlled by a switch relay G, and which relay in turn is controlled by a switch lever L^E located at a remote point, such for example, as a dispatcher's office. The control of the switch mechanism F by a neutral contact 55 and polar contacts 8 and 9 of relay G is standard in every respect and requires no detailed explanation. The circuit for relay G passes from terminal X of a suitable source of current through contact 4 of lever L^E, winding of relay G, front contact 44 of a master relay M, front contact 27 of track relay T^B, and contact 5 of lever L^E to terminal O of the

same source of current. The current thus supplied to relay G is of normal or reverse polarity according as lever L^E is in the normal or the reverse position, and, consequently, switch E will occupy its normal or its reverse position according to the position of the controlling lever. It will be noted that the circuit for relay G can not be closed unless track section B—C is unoccupied, and unless the master relay M is energized.

Traffic moving toward the right into section B—C is governed by two signals S^R_A and S^R_B, which signals are controlled by signal relays H^R_A and H^R_B in accordance with the usual practice. Traffic on the main track moving toward the left into section B—C is governed by a signal S^L_A which is controlled by a signal relay H^L_A, and traffic moving in the same direction on the side track Z is controlled by a signal S^L_B which is in turn controlled by a signal relay H^L_B. The signal relays H are controlled by a main signal relay J, and the relay J is controlled by a lever L^S located in the dispatcher's office. This lever is provided with pole changing contacts 6 and 7 which operate in the usual manner to supply current of normal or reverse polarity to relay J according as the lever is moved to its right-hand position or its left-hand position. When relay J is energized in the normal direction, relay H^R_A or relay H^R_B will be energized according as switch E is in the normal or the reverse position, this selection as to relays being determined in the usual manner by a circuit controller W operatively connected with the switch. It follows that signal S^R_A or signal S^R_B will then be cleared, depending upon the position of the switch. Similarly, when relay J is energized in the reverse direction, signal S^L_A or S^L_B will be cleared according as the switch is in the normal or the reverse position. The circuit for each of the relays H includes a front contact, such as T^B₁₈, of track relay T, the purpose of which is to prevent any one of the signals from indicating "clear" when the main section B—C is occupied, and to cause any signal which has been cleared to return to the "stop" position when a train enters this section. The control of the signals governing traffic over

the switch E is normal and standard in every respect and requires no detailed tracing of circuits.

The apparatus includes an eastbound approach relay P^A and a westbound approach relay P^C . Relay P^A is provided with a pick-up circuit which includes front contact 22 of track relay T^A and front contact 25 of relay T^B ; and relay P^A is also provided with a stick circuit which includes contact 22 of relay T^A and contact 37 of relay P^A but excludes contact 25 of track relay T^B . It follows that relay P^A will be energized when sections A—B and B—C are both unoccupied, but that it will become deenergized when a train moving toward the right enters section A—B and will remain deenergized until such train leaves section B—C.

The westbound approach relay P^C is controlled in a similar manner by track relays T^C and T^B for sections C—D and B—C, respectively, so that relay P^C is normally energized but will become deenergized when a train moving toward the left enters section C—D, and will remain deenergized until such train leaves section B—C.

The master relay M is controlled in part by an auxiliary master relay Q. Relay Q is provided with a pick-up circuit which passes from terminal X, through back contacts 28, 30, 32 and 34 of the H relays, back contact 42 of relay P^C , back contact 26 of relay T^B , back contact 39 of relay P^A , and the winding of relay Q to terminal O. It follows that in so far as this pick-up circuit is concerned, relay Q can become energized when and only when all of the signals indicate stop, both approach relays P are deenergized, and track relay T^B is likewise deenergized. Relay Q is provided with a stick circuit which includes the back contacts of the H relays but which passes from back contact 34, through front contact 45 of relay Q and the winding of this relay to terminal O. In other words, this stick circuit includes the back contacts of all of the H relays but excludes the back contacts of the P relays and of track relay T^B . It follows that when relay Q once becomes energized, it will remain energized as long as all of the signals remain in the stop positions. When relay Q is closed, a pick-up circuit for relay M becomes closed, which circuit passes from terminal X, through back contact 54 of a relay U, front contact 47 of relay Q and the winding of relay M to terminal O. Relay M is provided with a main stick circuit which passes from terminal X, through back contact 35 of signal relay H^L_B , back contact 33 of relay H^L_A , back contact 31 of relay H^R_A , back contact 29 of relay H^R_B , front contact 43 of relay M, and the winding of relay M to terminal O. This circuit is provided with a branch around contact 33 which includes front contact 41 of the westbound approach relay P^C . It is also pro-

vided with a branch around back contacts 31 and 29 of the eastbound signal relays, which branch includes contact 38 of eastbound approach relay P^A . The stick circuit for relay M and the branches for this stick circuit are in accordance with standard and usual practice and form no part of my present invention.

The pick-up circuit for relay Q is provided with another branch around contacts 42, 26 and 39, which branch includes a normally open, slow-acting device V, whereby after a given interval of time relay Q may be energized even though one of the relays P^A , P^C or T^B is closed, provided, of course, that all of the signal relays H are open.

The pick-up circuit for relay Q is provided with a third branch around contacts 42, 26 and 39, which branch includes front contact 53 of a normally deenergized relay U. The function and operation of relay U will be explained hereinafter.

I will now assume that the parts of the apparatus are in the positions in which they are shown in the drawing, and that the dispatcher desires to admit a train moving toward the right into section B—C. To do this, he will move signal lever L^s to the right, thereby clearing signal S^R_A . When the train enters the approach section A—B, it will deenergize the approach relay P^A , and inasmuch as signal relay H^R_A is energized, the stick circuit for relay M will be opened and so this relay will release. When the train enters section B—C, it will open track relay T^B , but approach relay P^C will remain closed, and, consequently, relay Q will not become energized. When the forward end of the train enters section C—D, relay P^C will become deenergized, whereupon, the main pick-up circuit for relay Q will become closed. This relay will then close the pick-up circuit for relay M, thereby releasing the approach locking of the switch E.

I will now assume that while the train moving toward the right is in section A—B the dispatcher desires that he wants to reverse switch E. To do this, he will restore signal S^R_A to the stop position, whereupon, it will be necessary to operate the slow-acting circuit controller V to close the pick-up circuit for relay Q, and when relay Q becomes energized it will cause relay M to become energized as before.

The apparatus thus far described has two important characteristics. One is that a light engine or other vehicle of a length not sufficient to simultaneously deenergize all three of the track relays T will, nevertheless, release the approach locking, because after such vehicle enters either of the approach sections, such as section A—B, the approach relay P^A will remain deenergized until the other approach relay P^C becomes deenergized, whereby the main pick-up circuit for relay Q will

be closed when the vehicle bridges the insulated joints between sections B—C and C—D. The other important characteristic is that if the track circuit current for section 5 B—C is momentarily interrupted while a train is in either of the approach sections, the approach locking will not be released, because the main pick-up circuit for relay Q will not become closed during such momentary interruption of track circuit current.

The function of relay U is to provide a time interval before the approach locking will be released in the event that signal S^L_B is cleared and is then returned to the stop position before it is accepted by a train. When signal S^L_B is cleared, that is, when relay H^L_B is energized, a pick-up circuit for a relay R will become closed through the front point of contact 36 of relay H^L_B . This will close a stick circuit for relay R, which includes front contact 49 of relay R and back contact 46 of relay Q. Then when relay H^L_B becomes de-energized, a heating element 51 of a thermo-sensitive relay Y will be supplied with current through the back point of contact 36 of relay H^L_B and front contact 50 of relay R. After a given interval of time, the thermo-sensitive relay Y will close its normally open contact 52, thereby energizing relay U. The third branch for the pick-up circuit of relay Q will then be closed through front contact 53 of relay U, with the result that relay Q will become energized. As soon as relay Q closes, it will open at contact 46 the stick circuit for relay R, and this relay will open at contact 50 the circuit for the heating element 51, with the result that contact 52 will open and relay U will become deenergized. When relay U releases, the pick-up circuit for relay M will become closed through back contact 54 of relay U and front contact 47 of relay Q, so that relay M will pick up and will release the approach locking for switch E.

Switch E is provided with a switch repeater relay K which is controlled in the usual manner by pole changing contacts 56 forming part of the switch circuit controller W. Polar contact 48 of relay K is open or closed according as switch E is in the normal 50 or the reverse position. When contact 48 is closed, it closes a shunt around back contact 42 of the westbound approach relay P^c , and so it follows that when the switch E is reversed and a train moving toward the right 55 enters the side track Z, relay Q will become energized when the train passes the fouling point of this side track, even though such train will not enter section C—D and so will not cause relay P^c to be deenergized.

Although I have herein shown and described only one form of apparatus embodying my invention, it is understood that various changes and modifications may be made 60 therein within the scope of the appended

claims without departing from the spirit and scope of my invention.

Having thus described my invention, what I claim is:

1. In combination, a stretch of railway track divided to form a main section B—C and two approach sections A—B and C—D on opposite sides of the main section, a track relay for each of said sections, a switch leading from section B—C into a side track, signals governing traffic into said main section B—C, signal relays for the control of said signals, an approach relay P^A provided with a pick-up circuit including front contacts of the track relays for sections A—B and B—C 70 and a stick circuit including a front contact of the former track relay but not of the latter, an approach relay controlled in similar manner by the track relays for sections C—D and B—C, an approach locking relay M , an auxiliary approach locking relay Q, a pick-up circuit for relay Q including back contacts of said approach relays and a back contact of the track relay for section B—C 80 as well as back contacts of said signal relays, a stick circuit for relay Q including back contacts of said signal relays, a pick-up circuit for relay M including a front contact of relay Q, a stick circuit for relay M controlled in the usual manner by said track and approach relays, and means for preventing operation of said switch unless relay M is closed.

2. In combination, a stretch of railway track divided to form a main section B—C and two approach sections A—B and C—D on opposite sides of the main section, a track relay for each of said sections, a switch leading from section B—C into a side track, signals governing traffic into said main sections B—C, signal relays for the control of said signals, an approach relay P^A provided with a pick-up circuit including front contacts of the track relays for sections A—B and B—C 100 and a stick circuit including a front contact of the former track relay but not of the latter, an approach relay controlled in similar manner by the track relays for sections C—D and B—C, an approach locking relay M , an auxiliary approach locking relay Q, a pick-up circuit for relay Q including back contacts of said approach relays and a back contact of the track relay for section B—C 105 as well as back contacts of said signal relays, a stick circuit for relay Q including back contacts of said signal relays, a relay R, a pick-up circuit for relay R including a front contact of the signal relay for the signal governing traffic from said side track into section B—C, a stick circuit for relay R including a back contact of relay Q, a slow-acting thermo-sensitive relay having a heating element and a normally open contact 52, a circuit for said heating element including a back contact of said last mentioned signal 110 120

125 130

- relay and a front contact of relay R, an auxiliary relay U controlled by said contact 52, an auxiliary pick-up circuit for relay Q including a front contact of relay U and back contacts of said signal relays, a pick-up circuit for relay M including a front contact of relay Q and a back contact of relay U, a stick circuit for relay M controlled in the usual manner by said track and approach relays, and means for preventing operation of said switch unless relay M is closed.

3. In combination, a stretch of railway track divided to form a main section B—C and two approach sections A—B and C—D on opposite sides of the main section, a track relay for each of said sections, a switch leading from section B—C into a side track, signals governing traffic into said main section B—C, an approach relay P^A, means for energizing relay P^A requiring that the track relays for sections A—B and B—C be closed and for subsequently keeping it energized as long as the track relay for section A—B remains closed, an approach relay P^B controlled in similar manner by the track relays for sections C—D and B—C, an approach locking relay M, an auxiliary approach locking relay Q, means for energizing relay Q provided that all of said signals are at stop and both of said approach relays and the track relay for section B—C are open, means for subsequently keeping relay Q closed as long as all of said signals remain at stop, means for energizing relay M when relay Q is energized and for subsequently keeping it energized until the signal governing traffic into section B—C from said side track is cleared or until a train approaches any of the other signals, when indicating clear, auxiliary means for energizing relay Q after a given time interval following the return to stop of said signal governing traffic from the side track, and means for preventing operation of said switch unless relay M is closed.

4. In combination, a section of railway track divided to form a main section and an approach section, a track relay for each of said sections, a switch leading from said main section into a side track, an approach relay having a pick-up circuit including a front contact on each of said track relays, a stick circuit for said approach relay including a front contact of the track relay for the approach section but not a contact of the other track relay, and approach locking means for said switch controlled in part by said approach relay and the track relay for the main section.

5. In combination, a stretch of railway track divided to form a main section B—C and two approach sections A—B and C—D on opposite sides of the main section, a track relay for each of said sections, a switch leading from sections B—C into a side track, signals governing traffic into said main section B—C, an approach relay P^A, means for energizing relay P^A requiring that the track relays for sections A—B and B—C be closed and for subsequently keeping it energized as long as the track relay for section A—B remains closed, an approach relay P^B controlled in similar manner by the track relays for sections C—D and B—C, an approach locking relay M, an auxiliary approach locking relay Q, means for energizing relay Q provided that all of said signals are at stop and both of said approach relays and the track relay for section B—C are open, means for subsequently keeping relay Q closed as long as all of said signals remain at stop, means for energizing relay M when relay Q is energized and for subsequently keeping it energized until the signal governing traffic into section B—C from said side track is cleared or until a train approaches any of the other signals, when indicating clear, auxiliary means for energizing relay Q after a given time interval following the return to stop of said signal governing traffic from the side track, and means for preventing operation of said switch unless relay M is closed.

In testimony whereof I affix my signature.

RONALD A. McCANN.
